Marshall & Hawley,

ATTORNEYS

UNITED STATES PATENT OFFICE.

JOHN FRANK BRUCKNER, OF UNION CITY, NEW JERSEY.

ADJUSTABLE BRACKET.

Application filed January 25, 1926. Serial No. 83,474.

This invention relates to brackets for supporting shade rollers and like structures.

When it is necessary or desirable to change or renew window shades, it often happens that the shade rollers available do not fit the brackets either because the brackets are too close together or too far apart. With the usual bracket construction, this necessitates changing the length of the roller or taking down and respacing the brackets, both of which procedures require time and are both-ersome.

This invention has for its salient object to provide an adjustable bracket of the character described that is simple and practical in construction and can be economically manufactured.

Further objects of the invention will appear from the following specification taken in connection with the drawings, which form a part of this application, and in which—

Fig. 1 is a front elevation of a bracket constructed in accordance with the invention;

Fig. 2 is an edge view of the structure shown in Fig. 1;

Fig. 3 is a sectional elevation of the structure shown in Fig. 1; and

Fig. 4 is a sectional elevation similar to Fig. 3 but showing the bracket for receiving the flat end of the shade roller spindle or shaft.

The invention briefly described consists of a bracket structure comprising a base in which is slidably mounted a bracket comprising a pair of shanks resiliently forced apart and having formed on or secured to their outer ends a bearing portion for supporting the shade roller. The bracket is constructed of resilient material and is so formed that the shanks are resiliently pressed apart and one of the shanks has a lip formed thereon adapted to coact with notches or serrations in the base to hold the bracket in adjusted position. Further details of the invention will appear from the following description.

In the form of the invention illustrated, the base comprises a back plate 10, a central plate 11 having an elongated slot 12 formed therein and a front plate 13 also having an elongated slot 14 therein, the slot 14 being narrower in width than the slot 12. One edge, preferably the lower edge of the slot 14 is serrated or provided with a plurality of notches 15.

The bracket has a pair of shanks 20 and 21 connected at their ends by a bearing or supporting portion 22. In the structure shown in Fig. 3, the portion 22 is adapted to support the round end of the shade roller spindle and in the structure shown in Fig. 4, the bearing portion is formed with substantially flat sides 24 and 25 adapted to coact with the flat end of the shade roller spindle to prevent the spindle from rotating as the shade roller is rotated.

In both forms of the invention shown, namely in Figs. 3 and 4, the bracket is formed of a single piece of material and the free ends of the shanks are bent laterally to form flanges 30 and 31. These flanges are positioned between the front plate 13 and the back plate 10 on the base as shown in Figs. 3 and 4.

One of the shanks, such as the shank 21, is provided with a downwardly extending lip 33 which is adapted to coact with the notches 15 and retain the bracket in adjusted position.

It will be obvious from the above description that the bracket can be adjusted to any desired position on the base by pinching together the shanks 20 and 21, thereby releasing the lip 33 from the notches 15. When the shanks are released, the lip will spring into one of the notches holding the bracket in adjusted position.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. An adjustable bracket construction for shade rollers comprising a flat base having a longitudinally recessed element therein, a longitudinal slot opening into said recess, one edge of the slot having a plurality of notches therein, and a bracket comprising a bearing portion, resilient shanks connected to the bearing portion and having offset ends slidably positioned in said recess, said shanks being resiliently pressed apart vertically, the lower shank having a lip engageable with said notches.

2. An adjustable bracket construction for shade rollers comprising a flat base having a

longitudinally recessed element therein, a longitudinal slot opening into said recess, one edge of the slot having a plurality of notches therein, a bracket formed of a single strip of resilient material and comprising a bearing portion at one end of the bracket, and a pair of shanks resiliently pressed apart vertically and having flanges at the

free ends thereof slidably positioned in the recess, one of the shanks having a lip adapted to engage said notches and retain the bracket in adjustable position. 10

In witness whereof, I have hereunto set my hand this 21 day of Jan., 1926.

JOHN FRANK BRUCKNER.
